UNITED STATES PATENT OFFICE

2,060,119

CALCULATING MACHINE

Ernest Racz, Detroit, Mich., assignor to Burroughs Adding Machine Company, Detroit, Mich., a corporation of Michigan

Application August 12, 1935, Serial No. 35,767

1 Claim. (Cl. 197—128)

This invention relates to a calculating machine and is especially concerned with the paper equipment thereof.

In many types of accounting work it is desirable 5 to keep a running record of the entries made over a given period while, at the same time, making different groups of entries on work sheets that are inserted and removed from the machine from time to time. Bookkeeping or accounting machines 10 have been developed for this work, said machines being known generally as "front-feed" machines because the work sheets that are inserted and removed are front-fed with respect to the platen. The present invention concerns this 15 type of machine, but instead of employing a complicated bookkeeping or accounting machine the invention proposes a simple, inexpensive front-feed device that can be used with a small calculating machine.

20 The general object of the invention is to provide an improved paper equipment for calculating machines.

A more particular object is to provide an improved front-feed paper equipment for a small 25 calculating machine.

Other objects and advantages of the invention will appear from the following specification and drawing.

An embodiment of the invention is shown in the 30 accompanying drawing in which:

Figure 1 is a perspective view of a machine with the invention applied thereto.

Fig. 2 is a partial right side elevation and section of the paper equipment with some of the 35 parts cut away to show others more clearly.

The invention is shown applied to a small calculating machine known as the "Burroughs portable", the details of which are disclosed in Horton Patent 1,853,050. It is to be understood that the 40 invention can also be used with other types of machines.

General calculating machine features

The machine has a plurality of depressible 45 amount keys 10 upon which items may be entered after which the machine is given a cycle of operation during which calculating mechanism contained within the housing 11 is operated. The cycle of machine operation is preferably initiated 50 by depressing a motor bar 12. A bank of control keys, such as the keys 13, is provided for conditioning the machine to perform different functions such as subtraction, total taking, sub-total taking, etc.

55 During a cycle of machine operation type bars

14 are differentially positioned after which a printing mechanism operates to drive the type bars rearwardly against a platen 15 rotatably mounted between two, spaced, stationary side plates 16 (Figs. 1 and 2). An ink ribbon 17 is positioned 5 to the rear of the type bars 14. This ribbon passes from one ribbon reel to another, the reels being contained in the housings 18.

The platen is normally line spaced during each 10 cycle of operation by a line space mechanism 20, operated from a movable member 21 of the calculating machine. The platen may also be line spaced by hand by means of the platen twirler 22.

Record sheet

The running record of entries is preferably 15 made upon a record sheet or strip 30 wound on a reel 31. In the embodiment of the invention shown, a second strip 32 having its rear surface carbonized is associated with the record strip 30 in order that, when the type strike the work sheet 20 immediately in front of the carbon strip, an impression will be made on the strip 30. The two strips are passed from the reel 31 under the platen 15 and upward as shown in Figs. 1 and 2, the strip 25 30 passing to the rear where it is wound on a rewind reel 33 supported on the arms 34. The carbon strip 32 is allowed to move upwardly to a position where the operator may tear it off from time to time.

The strips are line spaced with the platen by 30 being held in feeding relation thereto by feed rolls 40 of which one is shown in Fig. 2. These rolls are carried by arms 41 pivoted on a supporting blade 42, the arms being urged clockwise 35 as viewed in Fig. 2 by springs 43. The feed rolls may be released by means of a hand operated release lever 44.

The record strip is thus held about the platen 40 so as to move therewith and it serves to receive the entries made over a given period of time. After each entry, the strip is line spaced so that the entries are listed vertically.

Front-feed

The front-feed means includes a front-feed 45 paper chute for receiving and guiding a work sheet to front-fed position with respect to the platen.

Referring to Fig. 1, the chute comprises two 50 spaced side plates 50 and 51 which are slidably mounted on two cross shafts 52 and 53 carried by the stationary plates 16. The side plates of the front-feed chute are joined by a vertical cross plate 54 (Fig. 2), and by a horizontal cross plate 55

55 (Fig. 2). Mounted upon the vertical cross plate 54 are two wings 56 and 57 which project toward one another and which are spaced from the vertical plate to form a guiding pocket or space 5 to receive the work sheets and guide them toward front-fed position with respect to the platen.

For the purpose of further guiding the work sheets, and for holding them in position, a stationary plate 60 is provided which is fastened at 10 its ends to the stationary side plates 16. This plate extends downward in front of the platen and rearwardly under it. The plate assists in guiding a work sheet to front-fed position and it then turns the sheet toward the rear to position 15 the rear end of the sheet approximately horizontal. The plate is positioned with respect to the platen so that it will guide a work sheet to the rear of the ink ribbon 17, but the plate is sufficiently close to the platen so that when a sheet 20 is passed between the plate and the platen, and bent to the rear, the sheet will be held around the platen in printing position. It can still be moved either horizontally or vertically by hand but it will be held about the platen with sufficient firmness 25 to enable the type bars to strike it and make a clear impression.

The work sheet is guided further to the rear by a horizontal apron or guide 61 (Fig. 2) which holds the rear end of the work sheet in substantially horizontal position and allows the rear end 30 to project beyond the support where it can be grasped by the operator, if necessary. This feature is important where the entries are made near the top of the work sheet because it allows the 35 operator to grasp the rear end of the sheet to adjust the work sheet to proper line space position, or to pull the sheet out rearwardly.

A line finder is provided in the form of shoulders 62 and 63 on the stationary plate 60. The 40 plate is cut out to permit the type bars 14 to strike the work sheet and the shoulders 62 and 63 are formed so as to act as a guide line to enable an operator to adjust the work sheets in proper line space position while the work sheet is in vertical 45 and visible position.

The front-feed paper chute may be moved laterally to different positions to position the work sheets with respect to the printing mechanism and the platen in order to vary the horizontal 50 position of the entries on the sheet. As mentioned, the side plates 50 and 51 of the paper chute are slidably mounted on the shafts 52 and 53. A latch is provided for holding the chute in position although it will usually remain in the 55 position to which it is moved by the friction of the parts. The holding means comprises a latch 70 pivoted at 71 and urged clockwise as viewed in Fig. 1 by a spring 72. The rear end of the latch is bent downwardly and adapted to engage in a 60 slot 73 in a collar 74 fixed to the shaft 75. This latch normally holds the paper chute in the position as shown in Fig. 1. To release the chute, the latch 70 is rocked counterclockwise by hand which lifts the rear end of the latch out of the slot 73. 65 The chute may then be slid to the right and the latch released for entry into a slot 76 in another collar 77. As many collars may be provided as desired and the number of positions to which the paper chute may be moved can be varied to suit 70 the requirements. In the embodiment illustrated only two positions have been shown.

No holding means other than the devices already described is used to hold the work sheet in

front-fed position. The paper chute, assisted by plate 60, holds the free end of the sheet in substantially vertical position. The plate 60 holds the sheet around and closely adjacent the platen. The bend in the sheet serves to assist in holding 5 it in position for printing but allows it to be moved by hand, if desired.

With the machine shown it is not intended that the work sheet shall be line spaced with the platen because the work usually involves either only one 10 entry on the work sheet or, if two entries are made, they are in a horizontal alignment.

With the construction shown it will be evident that a continuous record of the entries can be made on the record sheet 30. The work sheets 15 may be quickly inserted and removed without manipulating any mechanism of any kind. All the operator needs to do, when he wants to insert a new work sheet, is to grasp the top of the one in the machine, pull it out, and then insert 20 another. After a sheet is inserted it is adjusted to the proper line space position by reference to the line finder 62-63. The sheet is usually stiff enough to be put down to its line space position. However, if the entry is wanted close to the top 25 of the sheet, the bottom end will project to the rear of the paper support so that the operator can grasp this to align the sheet, if he finds it more convenient. Also, if he desires, he can pull the sheet out by pulling rearwardly on it rather 30 than forwardly.

The work sheet can be shifted laterally with respect to the platen and the record sheet without disturbing either and without the manipulation of anything other than the latch 70 for releasing the chute. When the chute is moved it moves the work sheet laterally but the plate 60 that holds the sheet about the platen remains in position and thus keeps the work sheet in proper 35 position about the platen.

The structure shown is very simple and inexpensive, yet it provides a convenient means for keeping a running record of entries while at the same time allowing work sheets to be inserted and removed with great facility.

It is to be understood that the invention shown is for purposes of illustration only and that variations may be made in it without departing from the spirit and scope of the invention as defined by the appended claim.

I claim:

A front-feed machine of the class described having a paper support, a printing mechanism, a rotatable platen carried by said support, means on said support for holding a record sheet about 55 said platen in feeding relation thereto, a front-feed paper chute and guide for receiving and guiding a work sheet into front-fed position relative to said platen and record sheet, said guide also acting to hold said work sheet in a substantially vertical position in front of said platen with the lower end of said sheet projecting rearwardly under said platen and to hold it sufficiently tight to enable characters to be clearly printed by said printing mechanism on the vertical portion of 60 said sheet while holding it loosely enough to enable it to be moved laterally relative to said record sheet or to be quickly removed from the front or the rear without disturbing said record sheet, and means supporting said front-feed chute and guide 65 enabling it to be moved laterally relative to said platen.

ERNEST RACZ.
